Primary Examiner—Jeffrey Asch

(57) **CLAIM**

I claim the ornamental design for the communication device/gateway, as shown.

DESCRIPTION

FIG. 1 is a front view of the communication device/gateway;
FIG. 2 is a left side view thereof;
FIG. 3 is a top plan view thereof;
FIG. 4 is a right side view thereof;
FIG. 5 is a rear view thereof;
FIG. 6 is a perspective front view thereof;
FIG. 7 is a perspective rear view thereof; and,
FIG. 8 is a bottom plan view thereof.
